(57) **CLAIM**

The ornamental design for a wound patch as shown and described.

DESCRIPTION

FIG. 1 is a front view of a wound patch according to a first embodiment of our design;

FIG. 2 is a front view of a wound patch according to a second embodiment of our design;

FIG. 3 is a front view of a wound patch according to a third embodiment of our design; and,

FIG. 4 is a front view of a wound patch according to a fourth embodiment of our design.

The broken lines consisting of evenly spaced dash lines in the drawings depict portions of the wound patch that form no part of the claimed design.

The broken lines consisting of short and long dash lines encircling boundaries are to indicate that portions outside the boundaries form no part of the claimed design.

1 Claim, 4 Drawing Sheets
